UNITED STATES PATENT OFFICE

132,534

DESIGN FOR A HANDBAG FRAME

Joseph A. Lichter, Norwalk, Conn.

Application July 29, 1941, Serial No. 102,540

Term of patent 3½ years

To all whom it may concern:

Be it known that I, Joseph A. Lichter, a citizen of the United States, residing at Norwalk, in the county of Fairfield and State of Connecticut, have invented a new, original, and ornamental Design for a Handbag Frame, of which the following is a specification, reference being had to the accompanying drawing, forming part thereof.

Figure 4 is a similar end elevational view but with the frame in partly open position.

I claim:

The ornamental design for a handbag frame, as shown.

JOSEPH A. LICHTER.
